Primary Examiner — Kelley Donnelly(74) *Attorney, Agent, or Firm* — Ladas & Parry LLP(57) **CLAIM**

The ornamental design for a chair, as shown and described.

DESCRIPTION

FIG. 1 is a front elevational view of the chair showing my new design;

FIG. 2 is a top plan view thereof; and,

FIG. 3 is a right side elevational view thereof.

The broken lines shown in the drawings form no part of the claimed design.
